UNITED STATES PATENT OFFICE.

WILLIAM J. NESBITT, OF LOS ANGELES, CALIFORNIA.

HEEL-CUTTING APPARATUS.

1,250,489.

Specification of Letters Patent. Patented Dec. 18, 1917.

Application filed April 2, 1917. Serial No. 159,369.

To all whom it may concern:

Be it known that I, WILLIAM J. NESBITT, a citizen of the United States of America, residing at Los Angeles, county of Los Angeles, State of California, have invented a certain new and useful Heel-Cutting Apparatus; and I do hereby declare the following to be a full, clear, and exact description of the invention, such as will enable others skilled in the art to which it appertains to make and use the same.

This invention relates to heel cutting apparatus, and it may be said to consist in the provision of the novel and advantageous features and in the novel and improved construction, arrangement, and combination of parts and devices as will be apparent from the description and claims which follow hereinafter.

One object of the invention is to provide a novel and improved heel cutting apparatus in which the mounting for the heel clamping device permits of disposing the heel relatively to a hacksaw cutter to have the latter make straight or angular cuts through the heel according to the desire of the operator.

Another object of the invention is to provide a heel clamping device of a novel and improved construction.

Further objects of the invention are to provide a novel and improved heel cutting apparatus which is simple and compact in construction, economical to manufacture and use, easy and convenient to operate, and effective in action.

Other objects and the advantages of the invention will be apparent to those skilled in the art from a careful consideration of the following description of the preferred construction embodying the invention, taken in connection with the accompanying drawings in which

Figure 1 is a side elevational view of the heel cutting apparatus; Fig. 2 is an enlarged, partly sectional, side elevational view of the hacksaw and its connections; Fig. 3 is a cross sectional view of the lower part of the hacksaw and connections taken on the line 3-3 of Fig. 2; Fig. 4 is a front elevational view of the heel cutting appara-

tus; Fig. 5 is an enlarged broken side elevational view of the heel clamping device; Fig. 6 is a front, partly sectional, elevational view of the hacksaw and its operative connections; Fig. 7 is a partly broken plan view of the same, and Fig. 8 is an enlarged broken plan view of the mounting for the heel clamping device.

The supporting frame preferably consists of the post 10 which has on its upper portion the projecting part 11 to which is fastened by the bolts 12 the lower portion of the bracket 13 which is provided at its upper and lower ends with the arms 14 and 15 having openings in which is slidably fitted the rod 16 which carries the hacksaw 17. The latter has its upper and lower ends fitted in slots in one end of the arms 18 and 19, and it is pivotally connected to the arms 18 and 19 by the pins 20 which are passed through said arms and suitable openings in the hacksaw 17. The arm 19 has its other end fitted on the squared part 21 of the rod 16 and locked thereon by the nuts 22 and 23. In order to adjust the tension of the hacksaw 17 the arm 18 is preferably connected by the pivot 24 to one end of the arm 25 which latter has its other end fitted and suitably locked on the squared part 26 at the upper part of the rod 16, and a suitable screw 27 is mounted on the arm 25 and has its lower end part passed freely through the slotted rear end 28 of the arm 18 and provided with abutments 29 and 30 adapted to bear against the rear end part of the arm 18 when the screw 27 is adjusted by turning it on the arm 25.

To the wristpin 31 disposed on one side of the arm 19 is pivotally connected one end of the connecting rod 32 which has its other end pivotally connected to the wristpin 33 on the crank disk 34 which latter has connected thereto the sprocket wheel 35 which is driven by the sprocket chain 36 and is secured to the shaft 37 which is suitably mounted in the bearing 38 which is mounted on the bracket 39 on the lower part of the post 10.

As shown in this instance the heel clamping device consists of the upper plate 40 and the lower plate 41, which plates are

adapted to fit in the crease between the heel seat and the heel of the shoe 42; the lower plate 41 being secured by screws 42' to the bar 43, and the upper plate 40 being disposed on one side of the eccentric cam 44 which is mounted on the stationary pivot 45 and is provided with the operating handle 46. The bar 43 is preferably formed with the upright extension 47, and with the horizontal forward extension 48 at the upper end of upright extension 47.

The pivot 45 is connected to the forward end part of the extension 48. A facing 49 of rubber or other suitable material is provided on the cam 44 to prevent slipping on or marring of the heel of the shoe 42 when the cam is in engagement with the heel.

The heel clamping device is mounted on the dovetail guide 50 to one end of which adjacent to the hacksaw 17 is suitably secured the bar 43. The guide 50 is slidably mounted in a guideway which is provided in the table 51 which latter is connected by the pivot 52 to the table 53 which has on its underside the dovetail guide 54 which is slidably fitted in a corresponding guideway in the shelf 55 which is preferably pivotally connected to the post 10. As shown, the shelf 55 has suitably secured to its underside the lug 56 which is provided with the handle 57 and is mounted on the pivot 58 in the bifurcated upper end of the post 10.

The guide 50 and heel clamping device carried thereby is moved transversely to the table 53 and toward or away from the hacksaw 17 by the lever 59 which has its rear end connected by the pivot 60 to the lug 61 on the table 51, and is provided with a handle 62 on its forward end; said lever 59 being provided with a longitudinal slot 63 into which extends a pin 64 attached to the guide 50. When the guide is adjusted in position by the lever 59 it is locked in position by means of the projections 65 which are provided on the underside of the lever 59 and are adapted to fit in the notches 66 which are provided in the upper part of the table 51.

The table 51 can be turned horizontally on the pivot 52 by means of the handle 67. The latter has on its underside the dog 68 which is mounted on the pivot 69 and has one end thereof adapted to fit in the notches 70 provided in the end of the lateral extension 71 of the table 53. A spring 72 is interposed between the handle 67 and the dog 68 and is adapted to press the dog 68 into engagement with the extension 71 to lock the table 51 in adjusted position.

The handle 57 can be locked in adjusted position by means of the dog 73 which is slidably mounted on the spaced lugs 74 and 75 on the handle 57 and is adapted to engage the teeth 76 on the post 10; the dog 73 being

connected by the link 77 to the bell crank lever 78 which is pivotally mounted on the handle 57. The dog 73 is normally pressed into engagement with the teeth 76 by the spring 79 which is interposed between the lug 74 and the shoulder 74' on the dog 73.

The table 53 can be operated by means of the angular lever 80 which is mounted on the pivot 81 on the downward extension 82 at the forward end of the shelf 55 and is connected to the table 53 by the curved link 83 which has one end pivotally connected to the angular lever 80 and has its other end connected to the pivot 84 on the table 53.

From the foregoing description the construction, operation, and advantages of the apparatus will be understood by those skilled in the art. It will be seen that the heel of the shoe 42 is placed on the plate 41 to have the latter disposed in the crease between the heel and the heel seat of the shoe, and then the handle 46 is pulled upwardly to have the plate 40 disposed in the crease, and then the handle 46 is pulled upwardly until the eccentric cam 44 is in firm engagement with the heel of the shoe. The lever 59 can be operated to adjust the guide 50, and thereby the heel clamping device according to the amount that it is desired to cut off of the heel. If it is desired to make an angular cut longitudinally of the heel, the table 51 can be turned horizontally by the handle 67 to have the heel disposed at the desired angle to the hacksaw 17. If it is desired to make an angular cut transversely of the heel, the shelf 55 can be tilted to have the heel disposed at the desired angle to the hacksaw 17. By operating the lever 80 the table 53 can be moved to effect movement of the heel past the hacksaw 17 to have the latter cut the heel.

The construction which has been particularly illustrated and described admits of minor changes and modifications—wherefore the right is reserved to all such changes and modifications as do not depart from the spirit and scope of the invention which is defined in the appended claims.

I claim:

1. In shoe-heel cutting apparatus, the combination of a bar, a pivot on said bar, an eccentric cam mounted on said pivot and adapted to engage the heel of the shoe, a lower plate secured to said bar, and an upper plate disposed on the side of said eccentric cam, said plates being adapted to fit in the crease between the heel seat and the heel of the shoe, substantially as described.

2. In shoe-heel cutting apparatus, the herein-described heel clamping device comprising the combination of a stationary pivot, an eccentric cam mounted on said pivot and adapted to engage the heel of the

shoe, an upper plate disposed on the side of said eccentric cam, and a stationarily mounted lower plate, said upper plate and said lower plate being adapted to fit in the crease between the heel seat and the heel of the shoe, substantially as set forth.

In testimony whereof, I have signed my name to this specification at Los Angeles, county of Los Angeles, State of California, this 23rd day of March A. D. 1917.

WILLIAM J. NESBITT.
